DESIGN FOR A TABLE

Elijah J. Hammock, Hamilton, Ohio

Application August 7, 1943, Serial No. 110,849

Term of patent 14 years

To all whom it may concern:

Be it known that I, Elijah J. Hammock, a citizen of the United States, residing at Hamilton, in the county of Butler and State of Ohio, have invented a new, original, and ornamental Design for a Table, of which the following is a specification, reference being had to the accompanying drawings, forming part thereof.

I claim:

The ornamental design for a table, as shown.

ELIJAH J. HAMMOCK.
